(57) CLAIM

The ornamental design for a beverage maker, as shown and described.

DESCRIPTION

FIG. 1 is a perspective view of a beverage maker showing our new design;

FIG. 2 is a front view of the design shown in FIG. 1;

FIG. 3 is a rear view of the design shown in FIG. 1;

FIG. 4 is a right side view of the design shown in FIG. 1;

FIG. 5 is a left side view of the design shown in FIG. 1;

FIG. 6 is a top view of the design shown in FIG. 1;

FIG. 7 is a bottom view of the design shown in FIG. 1; and,

FIG. 8 is an additional perspective view of the design shown in FIG. 1.

The broken line showing of supporting elements in FIGS. 2-5 and 7, and rear components in FIGS. 3-8, is included for the purpose of illustration and forms no part of the claimed design.
